UNITED STATES PATENT OFFICE.

JAMES INGELLS, OF MUSKEGON, MICHIGAN.

EXTENSION-TABLE.

SPECIFICATION forming part of Letters Patent No. 760,630, dated May 24, 1904.

Application filed August 3, 1903. Serial No. 168,086. (No model.)

To all whom it may concern:

Be it known that I, JAMES INGELLS, a citizen of the United States, residing at Muskegon, in the county of Muskegon and State of Michigan, have invented certain new and useful Improvements in Extension-Tables; and I do declare the following to be a full, clear, and exact description of the invention, such as will enable others skilled in the art to which it applies to make and use the same.

My invention relates to improvements in extension-tables with removable leaves, such as are used in dining-rooms; and it consists in the peculiar construction and combination of devices hereinafter described and claimed.

One object of my invention is to effect improvements in the construction of the table-frames.

A further object of my invention is to provide improved means for locking the table-frames at any desired adjustment.

In the accompanying drawings, Figure 1 is an inverted plan view of a table embodying my improvements, the supporting-legs being indicated in dotted lines and the sections of the frame being closed against each other to reduce the table to its smallest compass. Fig. 2 is a sectional view of the same, showing the table-frames partly extended. Figs. 3, 4, and 5 are detail views.

In the embodiment of my invention I construct the table-frame in three sections. The end sections are indicated at 1 and the intermediate section at 2. Each of the end sections comprises an outer bar 3, an inner bar 4, and a pair of end bars 5, properly secured together. The intermediate section comprises a pair of parallel side bars 6 and a pair of end bars 7. To the ends of the intermediate section are secured side boards 8, which bear against the sides of the end sections 1 and are slidably related thereto, so that when the end sections are adjusted from the intermediate section to enable the leaves to be placed between them the joints or open spaces between the end sections and the intermediate section are covered by the said side boards. On the central portions of the bars 6 of the intermediate frame 2 are secured blocks 9 of suitable construction, having transverse openings

through which extend a pair of longitudinally-disposed lock-rods 10 of suitable length. The said lock-rods are secured to the blocks 9 by means of set-screws 11. The bars 4 of the end sections 1 are provided with blocks 12, the said blocks being slideable on the said lock-rods and the said blocks 12 having openings through which the lock-rods extend, enlarged at their outer portions, as at 13, coil-springs 14, disposed on the lock-rods, being housed in the said enlargements 13. At the ends of the lock-rods are stops 15, which are here shown as nuts screwed thereon. The said stops are adapted to coact with the blocks 12 to limit the extent of the movement of said blocks on the said lock-rods, and hence to limit the extent of the movement of the end frames 1 from the intermediate frame 2. The opposing sides of the end and intermediate frames are provided with coengaging studs 16 and openings 17 to receive them to strengthen the connections between the said end and intermediate frames when the end frames bear against the intermediate frame, as shown in Fig. 1.

Lock-plates 17 are provided with openings 18, through which the lock-rods 10 extend, the size of said openings being such that the said lock-plates when they are disposed obliquely with reference to the lock-rods impinge against the opposite sides of the lock-rods, as shown in Fig. 2, so that the said lock-plates are adapted to frictionally engage and firmly clamp said lock-rods. Each of the lock-plates is hinged at its inner end, as at 19, to a plate 20, secured to the under side of the table-top, either by the means here shown or by any other suitable means. Each lock-plate has a projecting arm 21 at its outer end engaged by an eye 22 of an operating-rod 23. The said operating-rods are slidably mounted in the blocks 12 and in hangers or bearings 24, the latter being near the outer ends of the end sections and the said operating-rods having their outer ends connected together in pairs by means of handle-yokes 25, whereby each pair of the operating-rods may be moved simultaneously to cause the lock-plates to disengage the lock-rods. The springs 14 bear against the lock-plates and keep the latter

normally in an inclined or oblique position with reference to the lock-rods, and hence frictionally engage therewith, so that the lock-plates and the lock-rods coact to lock the respective sections of the table-frame in any position in which they may be with respect to each other, whether the table be in its smallest compass or extended to any extent. Prior to readjusting the table by moving either of the end sections toward or from the intermediate section the handle-yoke 24 of the end section to be adjusted must first be moved manually to cause the lock-plates carried by the said end section to disengage the rods.

The side-boards 8, which cover the spaces between the end and intermediate sections, also serve to support the leaves which may be placed between the said sections, as will be understood. To support the intermediate portions of the said leaves and to secure the requisite rigidity between the sections when the table is extended, I provide slide-irons 26 of suitable length and of suitable size and shape cross-sectionally, the end portions of which operate in guides 27, which are secured to the under side of the table-top between the bars 3 4 of the end sections 1. The brackets 28 29 (shown in Fig. 1) serve for the attachment of supporting-legs for the table.

From the foregoing description, taken in connection with the accompanying drawings, the construction, operation, and advantages of my invention will be readily apparent, it is thought, without requiring a more extended explanation.

Various changes in the form, proportion, and the minor details of construction may be resorted to without departing from the principle or sacrificing any of the advantages of my invention.

Having thus described my invention, what I claim as new, and desire to secure by Letters Patent of the United States, is—

1. A table of the class described, having a plurality of relatively adjustable sections, lock-

rods fixed to one section and slidably engaging the other sections, lock-plates pivotally mounted on the slideable sections, and having openings to frictionally engage the lock-rods when said plates are in normal position, and means for moving the plates to cause the openings to clear the lock-rods.

2. A table of the class described, having a plurality of relatively adjustable sections, lock-rods fixed to one section and slidably engaging the other sections, lock-plates pivotally mounted on the slideable sections and having openings to frictionally engage the lock-rods when said plates are in normal position, springs to move said lock-plates to engaging position, and means to move the plates in position to cause their openings to clear the lock-rods.

3. A table of the class described, having a plurality of relatively adjustable sections, lock-rods attached to one section and slidably connected to another, pivotally-mounted lock devices to engage said lock-rods to lock the sections when adjusted, springs to normally engage said lock devices frictionally with the lock-rods, and means to disengage said lock devices from the lock-rods.

4. In a table of the class described, the combination of end sections and an intermediate section, lock-rods attached to the intermediate section and slidably connected to the end sections, pivotally-mounted lock-plates carried by the end sections and having openings to frictionally engage the lock-rods, springs coacting with the lock-plates to engage the latter with the lock-rods, and means to turn the lock-plates against the tension of the springs to the position required to disengage the lock-rods.

In testimony whereof I have hereunto set my hand in presence of two subscribing witnesses.

JAMES INGELLS.
